DESALTING CRUDE OILS

Filed July 14, 1945

UNITED STATES PATENT OFFICE

2,400,985

DESALTING CRUDE OILS

Bernard L. Evering, Chicago, Ill., and Arthur P. Lien, Hammond, Ind., assignors to Standard Oil Company, Chicago, Ill., a corporation of Indiana

Application July 14, 1945, Serial No. 605,018

5 Claims. (Cl. 252—330)

This invention relates to improvements in the removal of inorganic salts from crude oil. Inorganic salts in the form of chlorides of sodium, magnesium and/or calcium are frequently associated with crude petroleum oils, usually in the form of a salt brine emulsified with the oil; or in the form of crystalline salts usually surrounded by an oil film. The removal of salt from such crude oils by the usual methods present difficult problems. For example, when contacting the salt-containing oil with water, the oil film around the salt particles prevents the water from coming in contact with the salt crystal and as a consequence methods employing the washing of crude oil with hot water are not effective; even the addition of a demulsifying agent to the water has relatively small effect. The present invention provides a method for reducing the salt content of crude oil to a relatively low figure.

The removal of salt from crude oils prior to any distillation process or cracking process is necessary, since the presence of these salts, particularly when the concentration of salt exceeds about 20 pounds per 1000 barrels of oil, gives rise to considerable difficulties. They form deposits upon the heating surfaces and in the heating tubes of the heating equipment, such as stills, heat exchangers and the like, reducing its heating transfer capacity, they plug equipment and give rise to serious corrosion problems.

It is an object of the present invention to provide an improved method of desalting crude petroleum oils. Another object of the invention is to provide a method of removing inorganic salts, such as the chlorides of sodium, magnesium and/or calcium from crude petroleum oils without the use of large amounts of water, which introduces water-removal problems in such systems.

Still another object of the invention is to provide a method of obtaining crude petroleum oils having a relatively low salt content from high salt content crude oils. Other objects and advantages of the invention will become apparent from the following description thereof read in conjunction with the accompanying drawing which forms a part of this specification, and which is a diagrammatic flow diagram of one method of carrying out the herein-described invention.

In accordance with the present invention, salt-containing crude petroleum oils or salt-containing reduced crude oils, particularly such oils containing more than about 20 pounds of salt per 1000 barrels of oil are effective desalted to at least a salt content below that which is considered

detrimental, by treating such oils with liquid anhydrous hydrogen fluoride. The presence of large amounts of inorganic chlorides such as sodium, calcium and magnesium chlorides in crude oils is highly undesirable, since as hereinbefore stated, the presence of such salts in oils undergoing various distillation and/or heating processes undergo hydrolysis which produces hydrochloric acid. Dry hydrochloric acid itself does little damage, but when dissolved in water it becomes very corrosive. The treatment of such salt-containing crude oils or reduced crude oils with hydrogen fluoride converts these metal chlorides, particularly the alkali-metal and alkaline earth chlorides to the water insoluble fluorides, which however are soluble in the liquid hydrogen fluoride. These fluorides being less readily hydrolyzed do not form corrosive products; furthermore any remaining inorganic salts settle out more readily due to the emulsion destabilizing effect of the hydrogen fluoride treatment.

Generally, depending upon the amount of salt in the crude and the operating conditions from about 0.006 volume percent to about 60 volume percent or more of anhydrous HF can suitably be employed under pressures sufficient to maintain the hydrogen fluoride and the oil in the liquid phase. The amount of anhydrous hydrogen fluoride used can vary over a wide range, of from a trace sufficient only to react with the inorganic chlorides present in the crude oil, to as much as about 60 volume percent of HF when it is desired to operate with a liquid anhydrous HF layer. Depending upon the reaction temperatures and the quantity of hydrogen fluoride employed, pressure of from about atmospheric pressure to about 150 pounds per square inch can be used. A contact time of from about one minute to about one hundred and twenty minutes or more is suitable, although a contact time of from about five minutes to about sixty minutes is usually sufficient. The treatment is suitably conducted at temperatures of from about —25° F. to about 150° F., although temperatures of from about 32° F. to about 100° F., for example, temperatures of 70 to 80° F. are preferred. While it is preferred to carry out the desalting process at these temperatures, temperatures as high as about 400° F. can be used. At these higher temperatures pressures as high as about 1500 pounds per square inch are employed.

In carrying out the present invention, the salt-containing crude oil can be treated with stoichiometrical amounts of hydrogen fluoride to convert the chlorides to the corresponding fluorides,

and the hydrogen chloride formed in the reaction removed from the system. The amount of hydrogen fluoride to be employed can be predetermined by an analysis of the salt content of the crude oil prior to the treatment with the hydrogen fluoride. Since the hydrogen chloride, which is largely responsible for the corrosion in the processing of salt-containing crude oil, is removed from the system, and since the inorganic fluorides which are formed are more resistant to decomposition to form corrosive products, the hydrogen fluoride treated crude oil can be processed without encountering difficulties encountered by processing crude oils containing inorganic chlorides.

However, in a preferred embodiment of the herein-described invention, provision is made for the removal of the inorganic fluorides from the hydrogen fluoride-treated crude oil and the recovery and recycling of the hydrogen fluoride.

The preferred embodiments of our invention will be better understood by the following description thereof, which is given by way of illustration only and is not intended as limiting the scope of the invention.

Referring to the drawing, a salt-containing crude oil or a reduced crude oil from source 10 is introduced via line 11 into the reactor 12, wherein it is contacted with liquid anhydrous hydrogen fluoride from storage tank 13, introduced via pump 14 and line 15. The crude oil from source 10 is preferably first freed of the major portion of any water which may be present in the crude oil as it is received from the wells by well-known demulsifying and water removal means. Also, if the crude oil is highly viscous, it is desirable to lower the viscosity thereof by diluting the same with a diluent, preferably a paraffinic hydrocarbon diluent, such as hexane, saturated petroleum naphtha, or a liquefied normally gaseous saturated hydrocarbon, such as propane and the like. A hydrocarbon diluent oil from the source 16 can be introduced via line 17 into line 11, wherein it is admixed with the crude oil to be treated. The reactor 12 is suitably jacketed to provide means for controlling the temperature within the reactor, and if desired, can be provided with heating coils (not shown) in the bottom portion thereof. The reactor 12 is suitably a packed tower type reactor to provide thorough and intimate mixing and contacting of the crude oil and the hydrogen fluoride, although other suitable means of obtaining intimate contact can be employed. A temperature of 32° F. to 100° F., preferably of about 70° F. to 80° F. is maintained in the reactor and under a pressure sufficient, for example, from about atmospheric pressure to about 150 pounds per square inch to maintain the reactants in the liquid phase. Gaseous hydrogen chloride is withdrawn from the reactor through a line 18, while the mixture of crude oil and liquid hydrogen fluoride are withdrawn from the reactor 12 through a line 19 and introduced into a separator 20, wherein the mixture is permitted to separate into a lower hydrogen fluoride layer and an upper crude oil layer containing small amounts of liquid hydrogen fluoride, and possibly small amounts of hydrogen chloride. The crude oil layer from the upper portion of the separator 20 is passed via line 21 through a preheater 22, wherein it is heated to a temperature of from about 200° F. to about 450° F. and then introduced into a stripper 23. In the stripper 23, which is provided with heating means such as a heating coil 24 in the bottom portion thereof, and which

is maintained at a pressure of about 30 to 50 pounds per square inch, the desalinated crude oil is heated to a temperature of from about 350° F. to about 500° F., to free it of hydrogen fluoride together with some hydrogen chloride. The hydrogen fluoride and hydrogen chloride are withdrawn from stripper 23 through a line 25 and a condenser 26 to a flash drum 27 wherein hydrogen chloride is flashed off and withdrawn through vent 28. Hydrogen fluoride from drum 27 is withdrawn via line 29 and condenser 30 and introduced into line 15, and either recycled to the reactor 12 or sent to the storage tank 13. The desalinated crude oil stripped of hydrogen fluoride, is withdrawn from the stripper 23 via line 31, and if necessary, passed through a fluoride removal system 32 to remove any fluorides which may have been carried over from the reactor 12. The fluoride removal system is suitably a conventional bauxite tower or other suitable system to insure the substantial removal of any remaining fluorides which may be contained in the desalinated crude oil. The desalinated crude oil, substantially free of fluorides, is removed from the fluoride removal system through a line 33 for further refinery processing.

The hydrogen fluoride layer from the reactor 12 containing therein inorganic fluorides and sludge-like material is withdrawn from the reactor 12 via line 34, passed through preheater 35, wherein it is heated to a temperature of from about 100° F. to about 400° F. and preferably from about 200° F. to about 350° F. and introduced via line 36 into a hydrogen fluoride recovery tower 37, the bottom temperature of which is maintained between about 100° F. and about 500° F., and preferably between about 150° F. and 450° F., by means of a heating coil 38. The hydrogen fluoride from the tower 37 is passed via line 39 through a condenser 40 to a receiver 41. The bottoms from the tower 37 which comprise inorganic fluorides and sludge-like materials is removed via a line 42.

Water inevitably enters the system through crude oil feed stock and/or make-up hydrogen fluoride. To prevent this water from building up in the system, it is removed by by-passing a portion of the hydrogen fluoride from the tower 37 through lines 39 and 43 and heat exchanger 43a to a hydrogen fluoride-water azeotrope distillation tower 44, provided with a suitable heating means 45 in the bottom portion thereof. The hydrogen fluoride-water azeotrope in the tower 44 is maintained at a temperature of from about 185° F. to about 240° F. at atmospheric pressure and anhydrous hydrogen fluoride removed overhead through lines 46 and 39 and condenser 40 to the receiver 41, while aqueous hydrogen fluoride is removed from the bottom of tower 44 through a line 47. A portion of the anhydrous hydrogen fluoride in the receiver 41 is returned through pump 48 and line 49 to the top of the tower 44 to serve as reflux. The hydrogen fluoride in the receiver 41 can be passed via line 50 and pump 51 to the storage tank 13.

The effectiveness of liquid anhydrous hydrogen fluoride in desalting crude petroleum oils is demonstrated by the following example in which a crude petroleum oil comprising 75% Slaughter Crude Oil and 25% Wasson Crude Oil, and which contained about 216 pounds of salt per 1000 barrels of crude oil, was used. This crude oil composition was treated with 200 cubic centimeters of liquid anhydrous hydrogen fluoride per liter of crude oil at a temperature of about 78° F. for

about thirty minutes. At the end of this time the extract layer was removed and additional 200 cubic centimeters of fresh liquid anhydrous hydrogen fluoride per liter of crude oil were added to the raffinate and the mixture stirred for about thirty minutes at a temperature of about 77° F. The mixture was then permitted to separate into a raffinate layer and an extract layer and the latter then separated from the former. The raffinate layer was then heated to a temperature of about 400° F. to remove the last traces of hydrogen fluoride. During the treatment of the salt-containing crude oil with the hydrogen fluoride, the gas formed during the reaction was vented and analyzed as hydrogen chloride as evidenced by the formation of a heavy white precipitate when the gas was passed over a silver nitrate solution. The effective removal of salt is shown by the data in the following table:

TABLE
Desalting of crude petroleum oil

	Liquid HF (cc./liter of crude oil)	Lbs. salt per 1000 bbls. of crude oil
Crude oil.....	400	216 13.3

The above data show that the hydrogen fluoride treatment of the crude oil resulted in the removal of 94% of the salt to give a final value of 13.3 pounds of salt per 1000 barrels of crude oil. This is a marked improvement over conventional desalting methods which leave about 25 to 40 pounds of salt per 1000 barrels of crude oil.

While the present invention has been described by way of a specific example thereof, it is not intended that the same be limited to the particular example which has been given merely for the sake of illustration, nor by any theory as to the mechanism of operation of the invention, but only the appended claims in which it is intended to claim all other modifications coming within the scope and spirit thereof.

We claim:

1. The method of desalting a crude petroleum oil containing inorganic chlorides selected from the group consisting of alkali metal chlorides and alkaline earth chlorides comprising contacting said crude oil with liquid anhydrous hydrogen fluoride in an amount and for a time sufficient to convert said chlorides to fluorides with the formation of hydrogen chloride and removing said hydrogen chloride.

2. The method of desalting a crude petroleum oil containing inorganic chlorides selected from

the group consisting of alkali metal chlorides and alkaline earth chlorides comprising contacting said crude oil with at least stoichiometrical amounts, based on said inorganic chloride content of said crude oil, of liquid anhydrous hydrogen fluoride for a time sufficient to convert said chlorides to fluorides with a formation of hydrogen chloride and removing said hydrogen chloride.

10 3. The method of desalting crude petroleum oil containing inorganic chlorides selected from the group consisting of alkali metal chlorides and alkaline earth chlorides comprising treating said crude oil with liquid anhydrous hydrogen fluoride in sufficient quantities to react with substantially all of the chlorides, whereby said inorganic chlorides are converted to fluorides with the formation of hydrogen chloride, removing said hydrogen chloride from the liquid products, and removing unreacted hydrogen fluoride from the treated crude oil.

15 4. The method of desalting crude petroleum oil containing inorganic chlorides selected from the group consisting of alkali metal chlorides and alkaline earth chlorides comprising contacting said crude oil with liquid anhydrous hydrogen fluoride in sufficient quantities and under conditions to convert said chlorides to fluorides with the formation of hydrogen chloride and to form a diphasic separation of a raffinate phase comprising said crude oil substantially free of inorganic salts, and an extract phase, comprising liquid hydrogen fluoride containing therein inorganic fluorides, removing hydrogen chloride from the reactor, separating said raffinate and removing hydrogen fluoride from the said raffinate.

20 5. The method of desalting crude petroleum oil containing inorganic chlorides selected from the group consisting of alkali metal chlorides and alkaline earth chlorides comprising contacting said crude oil with liquid anhydrous hydrogen fluoride in a contacting zone, in sufficient quantities and under conditions to convert said chlorides to fluorides with the formation of hydrogen chloride and to form a diphasic separation of a raffinate phase comprising said crude oil substantially free of inorganic salts and an extract phase comprising liquid hydrogen fluoride containing therein inorganic fluorides, removing hydrogen chloride from the reactor, separating said raffinate phase and said extract phase and recovering hydrogen fluoride from said raffinate and extract phase, and recycling the recovered hydrogen fluoride to said contact zone.
